A. S. HASLAM.
APPARATUS FOR COOLING AIR.

No. 586,766.

Patented July 20, 1897.

UNITED STATES PATENT OFFICE.

ALFRED SEALE HASLAM, OF DERBY, ENGLAND.

APPARATUS FOR COOLING AIR.

SPECIFICATION forming part of Letters Patent No. 586,766, dated July 20, 1897.

Application filed October 14, 1895. Serial No. 565,613. (No model.)

To all whom it may concern:

Be it known that I, ALFRED SEALE HASLAM, knight, mechanical engineer, a subject of the Queen of Great Britain, residing at Union 5 Foundry, Derby, England, have invented certain new and useful Improvements in Apparatus for Cooling Air, of which the following is a specification.

According to this invention air to be circulated through rooms or stores is brought into contact with fixed vertical diaphragms cooled by being constantly wetted on both sides with brine or some uncongealable liquid. For this purpose I use a number of vertical corrugated 15 metal plates continuously supplied at the top with brine or other uncongealable liquid and having their bottoms in or above a receiver for the liquid. I drive a current of air by means of a fan or blower through the 20 spaces between the plates. The air being divided by the corrugated plates into a number of thin sinuous currents is cooled in its passage between the plates by impinging on them and the cold fluid trickling down the sides of each 25 plate.

Figure 1 of the accompanying drawings is a plan of the apparatus, and Fig. 2 is a vertical section.

A is the receiver, in which the brine is 30 cooled to a low temperature by the coils of pipe B or otherwise.

C is the fan or blower.

D is the pump, by which the liquid is raised to the upper tank E.

35 F F are the corrugated plates, and G G are the distance-pieces between them.

G' G' are inclined lugs on the distance-pieces, which alone come in contact with the plates, leaving narrow inclined slits or 40 passages G² for the liquid. The upper distance-pieces have projections G³, which together form the ends of the trough E, packing being placed between them, if necessary. The distance-pieces and plates are held together by 45 bolts H.

J is a trough with a perforated bottom for distributing the brine in the trough E.

The plates should be as near together as is practicable without injuriously checking the 50 flow of air.

Flat plates or plates with horizontal corrugations may be employed instead of plates

with vertical corrugations, as shown, but not so advantageously, because the air can pass between them in a straight line instead of 55 being compelled to wind backward and forward between the corrugations and impinge again and again against the cold liquid and the surfaces of the plates.

Having now particularly described and ascertained the nature of my said invention and in what manner the same is to be performed, I wish it to be understood that I do not claim generally apparatus in which air is cooled by being passed over plates wetted with cold 65 brine, which I am aware has already been done in several ways, each of which, however, has disadvantages; but

What I claim is—

1. The combination of a number of fixed 70 vertical plates, distance-pieces between the tops of the plates forming the perforated bottom of a trough, means for supplying cold brine or other uncongealable liquid to the trough and means for carrying the air or gas 75 between the plates.

2. The combination of a number of fixed 80 vertically-corrugated plates, distance-pieces between the tops of the plates forming the perforated bottom of a trough, means for supplying cold brine or other uncongealable liquid to the trough and means for carrying the air or gas 85 between the plates.

3. The combination of a number of fixed 85 vertical plates, distance-pieces between the tops of the plates forming the perforated bottom of a trough, means for supplying cold brine or other uncongealable liquid to the trough, means for carrying the air or gas between the plates, and a receiver for the cold 90 liquid into which the bottoms of the plates dip.

4. The combination of a number of fixed 95 vertically-corrugated plates, distance-pieces between the tops of the plates forming the perforated bottom of a trough, means for supplying cold brine or other uncongealable liquid to the trough, means for carrying the air or gas between the plates, and a receiver for the cold liquid into which the bottoms of the plates dip.

ALFRED SEALE HASLAM.
